UNITED STATES PATENT OFFICE.

JULIUS THEODORE JAEGER, OF IROQUOIS FALLS, ONTARIO, CANADA.

PROCESS AND APPARATUS FOR COOKING WOOD CHIPS.

Application filed April 1, 1922. Serial No. 548,853.

To all whom it may concern:

Be it known that I, JULIUS THEODORE JAEGER, a citizen of the United States of America, and resident of Iroquois Falls, Province of Ontario, Dominion of Canada, have invented certain new and useful Improvements in Processes and Apparatus for Cooking Wood Chips, and do hereby declare the following to be a full, clear, and exact 10 description thereof.

This invention relates to that step in the manufacture of paper wherein wood chips are enclosed in a vessel termed a digester and there exposed to an acid solution and 15 steam whereby the chips are softened and boiled until reduced to a pulpy mass, this digesting or cooking of the chips being continued for a suitable period to effect a saturation of the wood with the acid and softening of the fibre preparatory to an ejection 20 of the pulp from the digester for further treatment such as draining, washing and screening, in the paper making process.

Heretofore, in the acid treatment outlined 25 above, the contact of the acid solution and chips was effected by loading the digester with the chips and solution and saturating and cooking the chips by the admission of steam, the agitation of the chips to ensure 30 their treatment and saturation being dependent upon the ebullition resulting within the digester. This prior method presents the disadvantage, with others, that a considerably large charge of acid solution is required 35 in proportion to the quantity of wood chips to ensure the chips being completely immersed, and consequently requires a correspondingly large amount of steam as the greater amount of solution requires a greater 40 amount of steam and longer application of the latter to bring it to the boiling point. Furthermore in the process heretofore practised the acid solution is confined within the digester and consequently the action thereon 45 by the steam in heating the solution to the boiling point to agitate the mass and promote the thorough saturation of the charge of wood chips in the requisite manner is only secured through the slow process of 50 heating a stationary body of liquid. As this disadvantage has, in the past, been accentuated by admitting the steam at one end only of the digester, it will be apparent that the 55 digesting period has been needlessly protracted, being dependent upon the progression of the heating throughout the charge

from one end of the digester to the other and subject to the serious defect of uneven treatment owing to the variance of heat at points adjacent to the steam inlet and at 60 remote points near the opposite end of the digester.

The primary object of my invention is to improve existing paper pulp digesting processes and avoid the above mentioned 65 disadvantages by the establishment of a circulation of the acid solution, exposed to the heating element, through the digester and wood chip charge and admission of the heating element to the digester at different 70 points whereby the acid solution is circulated through the wood chips thus requiring a smaller charge of solution in proportion to the quantity of chips, to effect the requisite 75 saturation of the latter and calling for a correspondingly reduced amount of steam for heating, while speeding up the latter 80 action owing to the smaller body of liquid and circulation past the heating element. The admission of the steam at different 85 points further reduces the heating period and establishes a more uniform treatment of the charge due to the better distribution of the heating source throughout the mass, the different steam charges heating distinct portions of the digester content in a uniform manner and thus co-operating to heat the mass as a whole in a quicker and more even way.

Another object is to provide an apparatus 90 for carrying out my improved process.

The above and further objects and advantageous features of my invention will be hereinafter more fully described in the following detail specification and particularly 95 pointed out in the appended claims.

In my improved process a digester is loaded with wood chips and acid admitted with steam to heat the contents and bring them to the boiling point for an effective 100 softening and saturation of the chips. The acid such as sulphurous acid is admitted at or adjacent the top of the digester to percolate down through the chips thus exposing the whole body of chips to the acid without necessitating the use of such a quantity as would be necessary to completely immerse the chips, the small quantity of acid in comparison to the quantity of chips enabling the former to be quickly heated by the use of 105 a correspondingly reduced quantity of steam. The digester is preferably partially

filled with the acid solution from the bottom and through the medium of an injector, steam is utilized to draw this acid from the bottom of the digester and convey it to the top, the acid and steam being discharged upon the chips and passed through the latter from the top. The acid, preheated by its conveying steam, percolates down through the chips and is again carried to the top, this circulation quickly exposing it to the steam to rapidly raise its temperature and the passage of the acid through and through the body of chips, in conjunction with the application of steam to both ends of the 10 digester contents accelerating the attainment of a boiling temperature within the digester and effecting a thorough and uniform treatment of the contents.

For full comprehension, however, of my 20 invention reference should be had to the accompanying drawings forming a part of this specification, in which like reference characters indicate the same parts and wherein:

25 Fig. 1 is a front elevation of a paper pulp digester constructed in accordance with my invention;

Fig. 2 is a vertical section on line 2—2
Fig. 1; and

30 Fig. 3 is an enlarged detail section of the main coupling elbow.

Referring now to the drawings, 2 indicates the digester proper consisting preferably of a cylindrical steel vessel suitably 35 supported at 3 in upright position and having a top opening 4 and bottom opening 5, the top opening being adapted to be closed by a removable cover 6 and the bottom opening having the several pipes of the apparatus coupled thereto as will be now described.

40 A five-way elbow 7 coupled to the bottom opening 5 has a steam supply pipe 8 with valve 8^a leading to the bottom thereof through opening 9 and a branch steam pipe 10 with valve 10^a leading to the elbow from pipe 8 in front of valve 8^a through side opening 11 opposite to a side opening 12 to which a conduit 13 leading to the blow pits 50 (not shown) is connected, this conduit being controlled by valve 14 located adjacent to the elbow.

An acid supply pipe 15 controlled by 55 valve 16 communicates with the elbow through a side opening 17, an oppositely located side opening 18 of the elbow being covered by a grating 19 and connected to one side of an injector 20 by an acid pipe 21 controlled by a valve 22. The injector 60 20 preferably comprises a casing having a nozzle 23 at the bottom, open to the interior of the casing and directed into a combining tube 24 communicating with the interior of the casing and leading out through 65 the top of the latter, the nozzle being con-

nected to an auxiliary steam pipe 25 leading from the steam pipe 8 at a point beyond valve 8^a and controlled by valve 26 adjacent the injector. A pipe 27 leads from the combining tube 24 to the top of the injector, 70 passing through an opening in cover 6 and through top opening 4 where it terminates in a nozzle disposed at the top of the interior of the digester. Nozzle 28 preferably consists of a pipe length 29 flared at 75 its lower end at 30 and having a curved perforated head 31 attached thereto. As shown the head 31 is attached through the medium of bolts 32 carrying washers or distance pieces 33 spacing the head from the flared end of pipe 29 thus providing the nozzle with side openings in addition to the central or front openings constituted by the perforations of the plate.

Acid pipe 21 and auxiliary steam pipe 85 25 are connected by pipe 34 at a point between the elbow 7 and the valves 22 and 26 to provide a steam supply to elbow 7 through side opening 18 for a purpose to be presently explained, this pipe 34 being 90 controlled by valve 35.

My process is carried out with the above described apparatus as follows:

With opening 4 cleared of cover 6 and nozzle and with valves 8^a, 10^a, 14, 22, 26 95 and 35 closed, the digester is loaded with a full charge of wood chips and the acid solution admitted by opening valve 16, the solution passing through openings 17 and up through bottom opening 5 into the digester, 100 a portion of the acid, assisted by the static pressure within the digester, entering the injector through pipe 21. The acid is admitted only in sufficient quantity to partially fill the vessel, that is to about the 105 $\frac{3}{4}$ level as indicated particularly in Fig. 2. At this time valve 16 is closed and opening 4 also closed by the insertion of the acid nozzle and cover 6, the latter being fastened in a suitable manner and the digester interior with its pipe system thus sealed from the atmosphere.

The above preparation being completed steam valves 8^a and 26 and acid valve 22 are opened to direct steam through opening 9 of the main coupling elbow and bottom opening 5 of the digester into the interior of the latter and through pipe 25 into the injector. The steam admitted at the bottom of the digester comes into contact with the acid and wood chips and inaugurates the heating action which progresses upwardly through the digester contents and at the same time a similar heating action is inaugurated at the top of the digester as follows. Steam blowing from the pipe 25 passes through the injector, creating a vacuum therein and drawing acid with it up through pipe 27 to the nozzle at the top of the injector, the acid and steam being 125 130

sprayed from the nozzle over the top of the chips. The front and lateral openings of the nozzle distribute the discharge completely and uniformly over the top of the 5 wood chips thus evenly enveloping the latter and causing the acid to percolate down through the chips throughout the full cross-sectional area of the charge, the spraying of the hot acid over the top 10 of the chips protecting them from dry heat and avoiding the possibility of deterioration due to charring. In being conveyed from the injector to the top of the digester the acid is exposed to the steam 15 and thereby preheated before being discharged upon the chips; this admission of preheated acid and the steam at the top of the digester effecting a heating action at the top which progresses downwardly through 20 the digester contents. The described admission of steam at both ends of the digester heats the acid within the digester and inaugurates the boiling process at both top and bottom, the steam supplies at distinct points 25 within the vessel and acting upon separate portions of the contents, co-operating to quickly raise the temperature of the whole mass.

During the heating of the acid, condensation of the steam ensues owing to its contact with the cooler acid and the vessel becoming filled with a mixture of acid and condensed steam, circulation of the acid from bottom to top of the digester is retarded. To dispose of the excess liquid a relief pipe 36 is provided, this pipe leading from a point near the top of the digester to a cooler and reclaiming tank (not shown) and being controlled by a manually closed 40 valve 37 which is opened when the digester fills and allows the liquid to be drawn off from the top of the digester to re-establish the circulation, at which the valve 37 is closed. When the temperature of the acid 45 solution is equalized with that of the entering steam, condensation ceases and circulation is definitely established, being maintained by providing an outlet for gas naturally forming at the top of the digester. 50 This gas outlet comprises a gas relief pipe 38 leading from the top of the digester and controlled by a valve 39 which is kept shut excepting at such times as it is opened as required to relieve gas which accumulates 55 at top of digester with circulation.

In the circulation above explained, the acid content of the vessel is carried from the bottom of the digester to the top and thus passed through and through the body of 60 chips and into contact with the entering steam, thereby accelerating the heating of the acid and quickly bringing it to the boiling point, the boiling acid penetrating the chips and softening the wood fibre.

65 Heretofore as above mentioned, the digest-

ing vessel has been filled with acid to near the top and the acid maintained within the vessel without circulation, steam being admitted at one end, the heating action progressing from one end to the other of the stationary body of liquid. In comparison with this relatively slow attainment of boiling temperature progressively from one end of the digesting vessel to the other, the present process of inaugurating the boiling at 70 both ends of the digester and percolating the acid through the chips enables a lesser quantity of acid and correspondingly reduced quantity of steam for heating it to be used and more rapidly establishes the boiling temperature throughout the vessel due to the distribution of the heat sources at distinctly spaced points of the body of chips and the circulation established by the percolation method to carry the heated acid quickly 75 throughout all parts of the body of chips. The acid circulation furthermore effects a breaking up action upon the body of chips to agitate the mass so that from the commencement of the digesting process and 80 prior to the boiling period all the chips are intimately exposed to the heat to the end that a heating and subsequent boiling temperature is rapidly secured and a thorough 85 acid reaction effected resulting in a desirable 90 high degree of uniformity of product.

The boiling process is carried on for a suitable period, i. e., seven to eight hours, the valve 16 being then closed and the pulp blown from the digester to the pits, by 100 opening valves 10^a and 14, the above boiling period being of considerably reduced duration with respect to prior processes as the boiling with rapid circulation and percolation of heated acid over the chips is substantially uniform over the whole vessel and raises the temperature and effects the treatment of the chips faster than heretofore.

The action of injector 20 in drawing the acid from the bottom of the digester through elbow 7 and opening 18 to the pipe 21 naturally tends to carry certain of the chips with the acid, such chips being obstructed by the grating 19 from entering the pipe and in order to avoid the blocking of this 110 passage by the clogging of the grating the branch steam pipe 34 is provided, valve 35 being periodically opened to blow steam 115 inwardly through the grating and dislodge the accumulated chips.

120 What I claim is as follows:

1. An apparatus for the treatment of wood chips in the production of pulp, including in combination, a vessel for containing the chips, a steam supply pipe communicating with the vessel adjacent one end thereof, and acid supply for the vessel, an acid conveying pipe leading from one end of the vessel to the opposite end thereof into 125 which it discharges and means for circulat-

ing the acid from one end of the vessel, through said acid pipe, into the opposite end of the vessel and a nozzle upon the discharge end of the acid circulation pipe, such nozzle comprising a pipe length presenting a flared front end, a perforated head covering the flared end and means for securing the head in spaced relation with respect to the flared end of the pipe length to present side openings additional to the perforations of the head.

2. An apparatus for the treatment of wood chips in the production of pulp, including in combination, a vessel for containing the chips, a steam supply pipe communicating with the vessel adjacent one end thereof and means for circulating the acid out from one end of the vessel into the opposite end, such means including a steam pipe discharging into such opposite end of the vessel, an injector in the steam pipe, an acid conveying pipe leading from the vessel into the injector and a grating extending over the acid pipe at a point adjacent the vessel, to exclude chips from said pipe.

3. An apparatus for the treatment of wood chips in the production of pulp, including in combination, a vessel for containing the chips, a steam supply pipe communicating with the vessel adjacent one end thereof and means for circulating the acid out from one end of the vessel into the opposite end, such means including a steam pipe discharging into such opposite end of the vessel, an injector in the steam pipe, an acid conveying pipe leading from the vessel into the injector, a grating extending over the acid pipe at a point adjacent the vessel,

to exclude chips from said pipe, and a steam supply pipe leading into the acid pipe at a point between the grating and injector whereby steam can be blown through said grating towards the vessel to clear the grating of adhering chips.

4. An apparatus for the treatment of wood chips in the production of pulp including, in combination, a vertically disposed elongated vessel having top and bottom openings, a cover for sealing the top of the vessel, an elbow closing the bottom opening, a valve closed acid supply pipe leading into the elbow, a valve controlled main steam supply pipe leading into the bottom of the elbow, a valve controlled auxiliary steam pipe leading from the main steam pipe exteriorly of the vessel, through the top cover of the vessel and discharging into the top of the latter, a spraying nozzle upon the discharge end of the auxiliary steam pipe, an injector in the auxiliary steam pipe, a valve controlled acid conveying pipe leading from the elbow into the injector, a grating extending over the acid conveying pipe at a point adjacent the elbow, a valve controlled pipe connecting the auxiliary steam pipe and acid conveying pipe at a point between the valves of said pipes and the elbow, a valve controlled branch steam pipe leading from the main steam pipe into the elbow at the side thereof and a valve controlled pulp discharge conduit leading from the elbow at the opposite side to the branch steam pipe.

In testimony whereof, I have signed my name to this specification.

JULIUS THEODORE JAEGER.
